CASH REGISTER.

Application filed December 12, 1924. Serial No. 755,486.

This invention relates to improvements in cash registers having multiple totalizers adapted for a segregate analysis of transactions entered in the machine.

5 One of the several objects of the invention is to provide an improved machine containing a single operating mechanism and a plurality of independent totalizers, any one of which is capable of a preliminary adjustment to establish a co-operative relationship between it and the common operating mechanism whereby a particular transaction or amount may be recorded on any totalizer desired.

10 Another object of this invention is to normally cause the selection of a certain totalizer on each operation of the machine while the selection of another totalizer may be brought about by the depression of a special key.

15 A further object of the present invention is to provide an improved "throw-out" mechanism by means of which, when certain keys are operated, the totalizer which 20 has been predetermined for operation will be prevented from being actuated when the machine is subsequently operated.

25 In the accompanying drawings the improvements are shown in one form which 30 they might take when applied to or embodied in the British Patents Nos. 135,465; 140,363; 157,823; 157,824 and 157,825 of July 11, 1921, issued to Frederick L. Fuller. This embodiment is illustrative only, however, as the improvements are capable of modification and change to permit applying them to machines of various types, and it is the desire not to limit the use of the improvements to any one style of register.

35 40 With the above objects in view the invention consists in the novel combination and arrangement of parts, the features of novelty of which are pointed out in the appended claims and a preferred form of embodiment of which is hereinafter described with reference to the drawings accompanying and forming part of this application.

45 Of said drawings:

50 Fig. 1 is a vertical transverse sectional view taken through substantially the center of the illustrative machine in which the present invention has been embodied. This

view shows the operating keys, the driving mechanism for the power shaft and the differential mechanism which is under control 55 of the operating keys.

Fig. 2 is a vertical sectional view of the cash register taken on the section line 2—2 of Fig. 4. This figure shows the totalizer selecting and engaging mechanism, all of the 60 parts being shown in their normal positions.

Fig. 2^A is a vertical sectional view also taken on the section line 2—2 of Fig. 4 and illustrates the position the parts assume when an amount key is operated so as to 65 automatically engage the upper totalizer for operation.

Fig. 3 is a transverse sectional view taken on the same section line 2—2 of Fig. 4 showing the position the parts assume when a 70 clerk's key has been operated to select another totalizer for operation.

Fig. 4 is a top plan view of the totalizer selecting, transaction and amount keys, and the mechanism for selecting the totalizers 75 for operation.

Figs. 5 and 6 are detail views in section showing portions of the devices for automatically throwing out the "A" totalizer when the "B" key is operated.

Fig. 7 is a detail in section showing the devices under the control of certain transaction or throwout keys for disabling the 80 totalizer which has been predetermined for operation.

85 For convenience, principal features of the machine will be outlined and their general purpose and co-operation briefly explained in order to indicate the general operation of the machine as a whole, after which the preferred construction of the parts utilized to accomplish the functions explained will be described more in detail.

90 The machine which has been shown in the drawings and to which one form of the present invention has been applied is of the type known as "key operated" and is well known in the art. The amount keys are divided in banks and have associated therewith a differential mechanism for adjusting the type carriers and actuating the totalizer elements correspondingly. Two independent totalizers are provided so as to adapt the 95 register for a segregate analysis of transac-

tions and co-ordinated with these is a single set of actuating racks for differentially operating the totalizer elements.

In machines of this type it is desirable that one of the totalizers be normally set for operation so that when the amount keys are depressed alone the amount will be inserted in the normally operative totalizer. In order to adjust the remaining totalizer for operation there has been provided a special key which not only disables the mechanism which normally throws in the other totalizer, but may, if desirable adjust a special indicator and special type carrier. In the machine as herein disclosed the engaging mechanism is normally so adjusted that both totalizers would be engaged by an operation of the machine if no means were provided to prevent it. However, when the "A" totalizer is to be selected for operation, mechanism is automatically operated which disables the "B" totalizer selecting means and conversely when the "B" key is depressed to select its corresponding totalizer for operation, means directly under the control of the "B" key is operated so as to disable the engaging mechanism associated with the remaining or "A" totalizer.

While it is desirable to totalize separately the transactions of each clerk it is necessary at times to enter transactions which do not involve the receipt of cash, such as "charge" and "paid out," and it is essential that mechanism be provided to throw out or prevent the operation of either of the totalizers when these keys are operated. The mechanism for effecting this is under the control of the transaction throw-out keys and when operated will render ineffective the engaging mechanism associated with the totalizer which has previously been predetermined for operation.

The general organization and operation of the mechanism as a whole having been thus outlined, the preferred construction of the parts for accomplishing the above mentioned results will now be described more in detail.

General features.

The various parts of the mechanism are supported by a suitable framework comprising a base casting 20 and suitable side frames, one of which is shown in Fig. 1 and indicated by reference character 21. The main side frames are connected at their upper rear ends by a frame work 23 and cross connections in the form of tie bars 24 and 25 situated toward the front and rear of the machine respectively. The present machine is also provided with two intermediate and parallel supporting frames one of which is shown in Figs. 2 and 3 and indicated by reference character 26.

The illustrative machine is provided with

a number of keys divided into groups of amount keys and a special group of keys known as "transaction" keys. In addition to these keys there is provided a series of special keys known as "clerks" keys, the purpose of which is to exercise control over the selection of the totalizers and they may, if desired, operate special indicators and adjust type printing elements so as to leave a record of the clerks operating the machine.

The amount keys 27 are pivoted upon a transverse shaft 28 extending transversely of the machine and journalled between the side frames. The keys are guided in their reciprocating movements by slots formed in the cabinet and are further guided at their rearward ends by a vertically slotted plate 29 attached to the tie bar 25. Resting upon the rear ends of the keys is a key coupler 30 journalled at 31 between the side frames. The key coupler has a nose 32 co-operating at times with notches 33 formed in the rear ends of the keys 27. When the outer ends of the keys are depressed the key coupler 30 is rocked clockwise and the nose 32 thereon enters the notches 33 formed in the rear ends of the keys. The purpose of such key coupler mechanisms is well known in the art and need not be discussed herein.

Connected to the key coupler at 34 is a vertical reciprocating rack plate 35 provided with oppositely facing rack teeth 36 which alternately mesh with a gear 37 fast to the main operating shaft 38 journalled between the machine side frames 21. The arrangement of this mechanism is such that a reciprocation of the key coupler 30 by the keys will effect a complete rotation of the gear and the shaft 38 to which the gear is secured. Shaft 38 is provided with cams or other suitable devices for operating various parts of the registering and printing mechanisms and it is in this respect similar to the shaft G' of the Carney Patent #497,860—May 23, 1893.

In nearly all forms of cash register constructions it is essential after a registration is commenced that some device be provided to compel a complete performance of the started registration before a second operation can be effected. To this end any suitable mechanism may be provided and in the present instance it comprises a spring-pressed pawl 39 bearing against a ratchet wheel 40 secured to the main operating shaft 38.

The present machine is also provided with a device for attaching amount or transaction keys to the key coupler at the beginning of their movement so that any desired number of keys may be successively depressed and attached and the operation of all of them carried out and completed to effect the indication and registration of their

combined value by the depression of any one of the keys so attached. The keys which have been attached are given a full movement just as though they had all been simultaneously depressed by the hands of the operator and their full values are indicated, registered and printed. This enables the operator to indicate and register with one hand a registration requiring the operation of two or more keys since it obviates the necessity of spanning several keys with his hands in order to secure the simultaneous operation of the several keys. The device for accomplishing this will now be described.

Mounted on the flange of the key coupler 30 are a plurality of spring-pressed latch plates, one of which is shown in Fig. 1 and designated by reference character 41. Attached to the upper face of the key coupler are a plurality of rearwardly extending arms 42 which are apertured to receive studs 43 carried by ears 44 integral with the latch plates 41. A spring 45 projecting in sockets formed in both the latch plates and the key coupler tends to rotate the latch plate 41 until stopped by arms (not shown) integral with the ear 44 and contacting with the upper face of the key coupler.

Each bank of amount and transaction keys has associated therewith a separate latch plate while a pair of arms 42 is provided for supporting each latch plate at its extreme ends. In this manner each latch plate may be operated independently of any other latch plate.

For the purpose of raising the key coupler to what is known as the "coupling point" any of the amount or special transaction keys may be employed, but in the present instance the special keys designated as "clerks' keys" are especially provided to perform this function. The clerks' keys 46 and 461 (Fig. 4) are located at one end of the machine and are pivoted upon the key shaft 28 just as are the amount keys. Each clerk's key is provided with a cam surface 47 (Figs. 2 and 3) co-operating with a cam edge 48 on a shoulder 49 integral with and projecting from one end of the key coupler. The clerks' keys are notched at 50 so as to receive the shoulder and flange of the key coupler when a clerk's key is depressed to its coupling position. The edge 51 of the notch provides a stop face which engages the rearward edge of the flange of the key coupler and positively stops the motion of the key and key coupler as best shown in Fig. 3. From this it will be evident that when a clerk's key as 46 is depressed the cam edge 47 will co-operate with the cam edge 48 and raise the key coupler to a partially elevated position (Fig. 3) where it will be stopped by the engagement of flange 32 with the edge 51 of the key notch and

it will be held in this position by the full stroke mechanism previously described. However, when pressure is removed from the clerk's key the rear end of the key will drop back until a finger 52 thereon rests upon the upper edge of an angular member 53 fastened to the key coupler. At this time, any of the amount keys may be slightly depressed to engage them with and raise the coupler still further. During this further operation the angular portion 53 will be received by a cut-away portion 54 in the rear end of the clerk's key.

Whenever the coupler has been raised to its coupling point (Figs. 2 and 3) the latch plates 41 mounted on the coupler will be above the notches 33 formed in the rear ends of the amount and transaction keys and will bear against the concentric edges 55 of those keys. When it is desired to attach an amount key to the partially raised key coupler (Fig. 2) the desired key is depressed slightly resulting in the raising of the rear end of the key and by virtue of the concentric edge 55 co-operating with the rear edge of its associated latch plate 41 it will rock said latch plate counter-clockwise about its pivot 43 (Fig. 1) until the concentric edge clears the same. At this time the latch plate will be free to rock clockwise under the influence of the spring 45 thereby permitting it to engage the notch 33 formed in the rear end of the depressed key. In this manner the amount key is positively engaged or attached to the key coupler and in the same manner other amount and transaction keys related to other banks may be partially and successively depressed so as to attach them to the key coupler. As previously described, the completion of the operation of any of the attached amount or transaction keys will result in the simultaneous depression of all the keys which have been attached to the key coupler.

Differential mechanism.

The differential mechanisms and devices controlled by each of the various banks of amount keys are all similar in construction and operation and a description of one will suffice for all.

Each of the amount keys is provided with an upwardly extending arm 57 carrying at its extreme end a stud 158 which co-operates with a slot having two branches 58 and 59 formed in a cam plate 60 (Fig. 1). The cam plates 60, of which there is one for each key in a bank, are carried by a frame 61 loosely pivoted upon a transverse shaft 62. The slots 59 in the cam plates 60 are concentric with respect to the shaft 62, while the cam slots 58 are eccentric with respect to this shaft and to the key shaft 28. From the foregoing it will be evident that upon the depression of an amount key a differential

movement will be imparted to the frame 61. When the frame 61 is operated differentially by a key the studs associated with the undepressed amount keys in the same bank will 5 play in the arcuate slots 59 which permit the upward tilting of the frame 61 without interfering with the studs carried by the unoperated keys.

It is to be understood that there is a differential frame 61 for each group of amount keys. Each differential frame has secured or connected thereto so as to be movable therewith a segmental rack 63, the teeth of which are in continuous engagement with 15 the pinion 64 fast to an item type carrier 65 (Fig. 1) journaled on a shaft 661. Thus it is evident that when the keys are depressed their corresponding racks 63 are moved and are given a differential degree 20 of movement so that the item type wheels 65 will be rotated correspondingly. When suitable impression means is actuated the item type wheels will print characters indicating the amount of the transaction entered 25 in the machine. No showing has been made of any impression means since it does not constitute any part of the present invention, but reference may be had to the British patents mentioned for the disclosure of one suitable form of such means.

Below the item type carriers are two totalizers, the upper of which is, for convenience, designated as the "A" totalizer and the lower as the "B" totalizer. These totalizers may be used for the purpose of registering amounts for separate departments, for clerk's or any other segregated analysis desired. Each totalizer comprises a frame 66 carrying a shaft 67 supporting a series of 35 accumulating elements 68. Each element has attached thereto a pinion (not shown) which is adapted to engage the teeth of the actuating racks 63. The totalizer frames 66 are journaled at 69 between the parallel 40 supporting frames 26 and are adapted to be rocked about this point as a pivot to bring the pinions into and out of engagement with the actuating racks 63.

50 *Totalizer engaging mechanism.*

In the type of machine shown in the drawings it is desirable that the registering devices be so arranged that either one or the other of the same may be brought into 55 operative connection with the operating means so that the clerks may register the amounts of their sales independently. It is, moreover, desirable that one of the totalizers be engaged automatically whenever the 60 amount keys are operated and that the other totalizer be placed in operation under the control of a special clerk's key which is operated in conjunction with the desired amount keys. It is also desirable that means in the 65 form of transaction keys be provided for

throwing out or disengaging the totalizer which has previously been selected for operation.

In the present embodiment of the invention the upper totalizer has been appropriated to receive the amounts registered by the "A" clerk, while the lower or remaining totalizer is placed under the control of the "B" clerk. While a series of clerk's keys has been referred to in the present application, it is not essential that two keys be provided since the selection of one of the totalizers may be placed under the control of a single clerk's key and the mechanism is so arranged that operation of the amount keys 70 without depressing the special clerk's key will automatically engage the "A" totalizer with the actuating racks. The "A" key is provided primarily for the purpose of lifting the key coupler to the coupling position 75 so that the amount keys can be attached thereto successively as desired. By a careful manipulation of one or more of the amount keys the key coupler can also be lifted to this particular position to attach other amount keys to the coupler, but there is nothing to prevent the movement of these keys beyond the coupling point or to serve as a stop when this point is reached. It is 80 desirable, therefore, to provide a second 85 clerk's key so that when it is operated the coupler will be positively stopped at the coupling position and will not be lifted beyond this point, such as would be the case 90 if an amount key were operated heavily and quickly. 95

The devices for engaging the desired totalizers will now be described. Pivotedly mounted upon a transverse shaft 70 situated near the base of the machine and extending 100 between side frames 21 is a lever 71 carrying rollers 72 co-operating with a pair of complementary cams 73 attached to the rotation shaft 38. The lever 71 is riveted to a bail 72' and attached to the bail at 105 one end is a forwardly extending lever 74 secured to which is a pin 75. The profile of the complementary cams is such that the bail and lever 74 are given an oscillating movement during each operation of the machine 110 and this movement will effect the engagement of the pinions of the desired totalizer with the actuating racks by means which will be described. 115

Adjacent to the left parallel supporting frame 26 are the totalizer control slides 76 and 77. The "A" totalizer control slide 76 is provided with a slot which engages the "A" totalizer supporting shaft 67, said slot being formed with an effective portion 771 and an ineffective portion 78. In a similar manner the "B" totalizer control slide 77 has an effective portion 79 and an ineffective portion 80. Both of these slides are apertured at their upper extreme ends at 81 to 120 125 130

engage the item wheels supporting shaft 661, while at their lower ends the slides are slotted at 82 to engage the stud 75 carried by the lever 74. Due to the above construction 5 it will be evident that whenever a slide is shifted by means which will hereinafter be described its effective portion co-operating with the totalizer wheel supporting shaft will rock the totalizer frame about its pivot 10 to bring the pinions into and out of engagement with the actuating racks.

Loosely mounted upon the pin 75 are two totalizer throw-out plates, the one associated with the lower "B" totalizer indicated by reference character 85 and the one associated with the "A" totalizer by reference character 86. As best shown in Fig. 2, the throw-out plate 86 is provided with a cam slot 87 engaging a pin 88 carried by the "A" totalizer engaging slide 76. In a similar manner the "B" throwout plate 85 is likewise provided with a cam slot 89 engaging a pin 891 (Fig. 2^A) carried by the "B" engaging slide 77. The configuration 25 of the cam slots in the plates 85 and 86 is such that when either plate is rocked on the pivot 75 from the normal position shown in Fig. 2 it will, through the pin 88 or 891 raise its associated totalizer slide. The purpose 30 of this mechanism will appear later as the specification progresses.

Loosely mounted upon a shaft 90 journaled between the side frames are a plurality of throwout bails, 91 indicating the one associated with the "A" totalizer and 92 the one associated with the "B" totalizer. As best shown in Figs. 2^A and 4 the bail 92 has integral therewith a downwardly extending arm 93 bifurcated at its lower extremity to receive a pin 94 carried by the "B" totalizer throw-out cam plate 85. In a similar manner the throw-out bail 91 has integral therewith a downwardly extending arm 95 co-operating with a pin 96 carried by the cam throw-out slide 86. Associated with the "B" throw-out bail 92 is a plate 97 provided with a shoulder 98 normally engaging the under side of the bail 92. The plate 97 is pivoted at 981 to an arm 99 loose upon the key shaft 28 and carrying a pin 100 normally contacting with an extension 101 integral with the bail 72'. As shown in Fig. 3 a spring 102 extends from a forward extension of the plate 97 to a shaft 103 secured between the machine side frames. It should also be stated at this point that each of the bails 91 and 92 is provided with rearwardly extending arms 931, to which springs 941, are attached, the function of these 55 springs being to return the throw-out bails and associated members to their normal position after being operated.

As previously stated, the totalizer engaging device are so arranged that the "A" 60 or upper totalizer will be thrown into op-

eration whenever the key 46 is depressed, or if so desired, whenever the selected amount keys are depressed alone. The manner in which the engaging devices operate so as to automatically throw the "A" counter into operation and to disable the "B" counter will now be described, reference being had particularly to Fig. 2^A. As shown in this figure, an amount key has been operated sufficiently to render the engaging mechanism effective, so that upon a continued operation of the machine the item will be entered into the upper or "A" totalizer. When the key coupler is rocked from the position shown in Fig. 2, the complementary cams 73 operating upon the arm 71 will rock the bail 72' clockwise and through the arm 74 and the connection to the engaging slide 76, comprising the cam plate 86 and the pin 88, will move the slide 76 downwardly sufficiently to bring the effective portion 771 of the slot in the "A" totalizer engaging slide in co-operation with the pin 67, thereby rocking the totalizer frame counter-clockwise about its pivotal point 75 and bringing the totalizer pinions into engagement with the actuating racks. Upon a continued depression of the keys the item will be entered in the totalizer.

It will be noted that if no preventive means were provided the pin 75 would also draw downwardly the "B" engaging slide 77 and force the "B" totalizer into mesh with the actuating racks. This, of course, would permit the entering of the item in the "B" totalizer; and in order to segregate the entered items it is necessary to provide devices for automatically disengaging the "B" totalizer whenever the "A" totalizer is to be rendered effective. The operation of the mechanism for automatically effecting this will now be described.

When the bail 72' is rocked clockwise the extension 101 acting upon the pin 100 carried by the arm 99 will lift the plate 97 and through the shoulder 98 also rock the "B" throw-out bail 92 in a clockwise direction. Clockwise movement of the bail 92, through the arm 93 and the pin 94 will rock the "B" throw-out plate 85 rearwardly. At the same time that the throw-out plate was being forced rearwardly the arm 74 was moving the "B" totalizer engaging slide 77 downwardly. The net result of these two movements is that the "B" engaging slide 77 will remain substantially in the position shown in Figs. 2 and 2^A and the "B" totalizer will therefore not be thrown into operation.

The operation of the mechanism for effecting the entering of items in the "B" totalizer and simultaneously throwing out the upper or "A" totalizer will now be described. The position that the parts assume when the key 461 is depressed so as to throw the corresponding totalizer into mesh with the actu-

ating racks is shown in Fig. 3 of the drawings. When the "B" totalizer is to be selected for operation it is necessary to operate the throw-out mechanism associated with the remaining totalizer and the means for effecting this is directly under control of the key 461. When this key is depressed the pin 462 carried thereby operates upon a cam plate 105 loosely mounted upon the 10 shaft 90 and provided with an extension 106 (Figs. 3 and 6) co-operating with the under side of the "A" throw-out bail 91. While the arm 74 is being moved downwardly the key 461 simultaneously operates 15 upon the cam plate 105 and through the bail 91 rocks the "A" throw-out slide 86 rearwardly and in the manner previously described with respect to the "B" throwout mechanism it prevents the "A" totalizer from 20 being forced into mesh with the actuating racks.

It is, of course, necessary to disable the means which automatically throw out the "B" totalizer whenever the amount keys 25 alone are operated so that the "B" totalizer will be placed into operation. The mechanism for effecting this is also placed under control of the key 461 and is shown in detail in Fig. 5. As shown in this figure co- 30 operating with the "A" totalizer throw-out bail 91 which is moved each time the key 461 is depressed, is a plate 107 hooking over the bail 91 and provided with a pin 108 which lies within a slot 109 formed in the 35 plate 97. When the key 461 is depressed the bail 91 will be rocked clockwise and through the pin 108 carried by the plate 107 will contact with the rearward edge of the slot 109 and force the plate 97 rearwardly 40 against the tension of the spring 102 until the shoulder 98 on the plate 97 is disengaged from the underside of the bail 92. Upon a continued movement of the plate 97 it 45 will move up and remain in the position shown in Fig. 3, being held by the full stroke mechanism previously mentioned. Due to the disabling of this automatic throw-out mechanism while the arm 74 is being forced downwardly, it will, through the pin 75 and 50 plate 85 draw downwardly the "B" engaging totalizer slide 77 and thru the medium of the effective portion 79 of the slide engaging the shaft 67 carried by the "B" totalizer frame will rock the latter about its pivotal 55 point thus bringing the "B" totalizer pinions into engagement with the actuating racks.

It is desirable that when a transaction key, such as "charge" or "paid out", which does 60 not involve the receipt of cash is operated that neither of the totalizers be operated regardless of which one has been predetermined for operation since the totalizers should indicate only the actual cash received. 65 The special transaction throwout keys 110

are each provided with pins 111 which operate upon cam plates 112 (Fig. 7) loosely mounted upon the shaft 90 and provided with upwardly extending lugs 113 of sufficient width to engage the under side of both 70 throwout bails 91 and 92. It will be quite evident from inspection of Fig. 2^A that if a transaction throwout key should be depressed after an amount key has been operated sufficiently to throw in the "A" totalizer 75 75 it will, through the lug 113 elevate the bail 91 so that it will rock the "A" totalizer throw-out plate rearwardly. This movement will raise the engaging slide 76 from the position shown in Fig. 2^A to its central 80 position thereby camming the totalizer shaft 67 forwardly and disengaging the "A" totalizer pinions from the actuating racks. Since neither totalizer will then be in mesh the amount entered will not be registered but 85 merely indicated and recorded.

In the same manner if the "B" clerk desires to enter a transaction, such as "paid out", and "charge" he will first depress the key 461 and subsequently depress the corresponding transaction throw-out key. Depression of one of these keys will, through the cam plate 112 raise both of the bails 91 and 92 (Fig. 7) thereby forcing both the "A" and the "B" totalizer throwout cam 90 plates 85 and 86 rearwardly, and disengaging both totalizers from mesh with the actuating racks. Thus even though the raising of bail 91 serves to disable the automatic movement of bail 92 the latter is directly 95 shifted by the plate 112. Since both of the totalizers are now in their normal positions the item entered in the machine will not be registered upon either totalizer.

While the form of mechanism herein 105 shown and described is admirably adapted to fulfill the objects primarily stated it is to be understood that it is the desire not to confine the invention to the one form of embodiment shown and described, as it is susceptible 110 of embodiment in various forms, all coming with the scope of the claims which follow.

What is claimed is:

1. In a cash register the combination with 115 a series of operating keys, a plurality of totalizers, operating means therefor, a drive shaft operated by said keys, means operated by the drive shaft and common to both of the totalizers for engaging a desired totalizer with the operating means, and means under the control of the operating keys for automatically disabling one of the totalizers while the other is being engaged with said operating means.

2. In a cash register, the combination with 120 a series of operating keys, a plurality of totalizers adapted to be moved from an ineffective to an effective position, and means operated by any operating key for auto- 125 130

matically retaining one of the totalizers in an ineffective position while the other totalizer is being moved to its effective position.

3. In a cash register, the combination with a series of amount keys, a special key, a plurality of totalizers adapted to be moved from an ineffective to an effective position, means under control of the amount keys for automatically retaining one of the totalizers in an ineffective position and operable while the other totalizer is being moved to its effective position, and means under the control of the special key for rendering the effective totalizer ineffective.

4. In a cash register, the combination with a series of keys, a plurality of totalizers mounted at equal radial distances from a shaft, a drive shaft, means driven by the drive shaft tending normally to render all of the totalizers effective, and means under control of the driven means for automatically rendering one of the totalizers ineffective.

5. In a cash register, the combination with a series of amount keys, a special key, a plurality of totalizers, means under the control of the special key or amount keys for rendering one of the totalizers ineffective while the other is rendered effective, transaction keys, and means under control of the transaction keys for rendering the effective totalizer ineffective.

6. In a cash register, the combination with a series of amount keys, a drive shaft operated thereby, a plurality of totalizers, means connected to each totalizer and operated by the drive shaft for rendering the corresponding totalizer effective, and devices controlled by said drive shaft for disabling one of said means.

7. In a cash register, the combination with a series of amount keys, a plurality of totalizers adapted to be moved from an ineffective to an effective position, cams, one for each totalizer and operable for retaining the corresponding totalizer in its ineffective position and means controlled by the amount keys for operating one of the cams independently of the other.

8. In a cash register, the combination with a series of amount keys, a plurality of totalizers adapted to be moved from an ineffective to an effective position, cams, one for each totalizer for retaining the corresponding totalizer in its ineffective position, a clerk's key and means controlled by either the amount keys or clerk's key for operating one of the cams independently of the other.

9. In a cash register, the combination with a series of amount keys, a plurality of totalizers adapted to be moved from an ineffective to an effective position, cams, one for each totalizer for retaining the corresponding totalizer in its ineffective position, means operated by said amount keys for operating

one of the cams, a clerk's key and a transaction key and means operated thereby for operating the remaining cam.

10. In a cash register, the combination with a series of amount keys, a plurality of totalizers, a corresponding number of slides having cam slots, members carried by the totalizers, co-operating with said cam slots, means for operating said slides whereby the totalizers will be moved to their effective positions and means controlled by the amount keys for preventing the movement of one of the slides.

11. In a cash register, the combination with a series of amount keys, a plurality of totalizers, a corresponding number of slides for moving the totalizers from their ineffective to effective positions, means for operating both slides, a clerk's key and means controlled by either the clerk's key or amount keys for preventing the movement of one slide while the other is operated.

12. In a cash register, the combination with a series of amount keys, a plurality of totalizers, means for rendering said totalizers effective, devices controlled by the amount keys for automatically preventing one of the totalizers from being rendered effective while another is placed in operation, a clerk's key, and means controlled thereby for disabling the said devices.

13. In cash register, the combination with a plurality of totalizers, an operating mechanism, totalizer engaging mechanism normally in condition for engaging both totalizers, means controlled by the operating mechanism for disabling the engaging mechanism associated with one totalizer and simultaneously permitting the effectiveness of the engaging mechanism associated with the remaining totalizer.

14. In a cash register, the combination with a plurality of totalizers, disabling devices, one for each totalizer, means controlled by the operating mechanism for disabling one totalizer, a clerk's key having means controlled thereby for disabling the other totalizer, and a transaction key having means for disabling the totalizer which has not been disabled by the previously mentioned means.

15. In a cash register, the combination with an operating mechanism, a series of amount keys, a differential mechanism controlled by the amount keys, a plurality of totalizers normally disengaged from the differential mechanism, operating mechanism for automatically engaging one of the totalizers with the differential mechanism and disabling the remaining totalizer, and a key adapted to operate the operating mechanism and to reverse the effectiveness of the totalizers.

16. In a machine of the class described, a plurality of totalizers, separate mechanisms for each totalizer normally effective to cause

- engagement of all of said totalizers, main operating mechanism and means automatically controlled thereby to render one of said engaging mechanisms ineffective.
17. In a machine of the class described, a plurality of totalizers, separate mechanisms for each totalizer normally effective to cause engagement of all of said totalizers, main operating mechanism, means automatically controlled thereby to render one of said engaging mechanisms ineffective, and a key for disabling said automatic means and simultaneously rendering another of said engaging mechanisms ineffective.
18. In a machine of the class described, a plurality of totalizers, separate mechanisms for each totalizer normally effective to cause engagement of all of said totalizers, main operating mechanism, means automatically controlled thereby to render one of said engaging mechanisms ineffective, a key for disabling said automatic means and simultaneously rendering another of said engaging mechanisms ineffective and, a series of transaction keys for rendering said first mentioned engaging mechanism ineffective.
19. In a machine of the class described, a totalizer, actuators therefor, an operating mechanism, a slide for controlling the engagement of the totalizer with the actuators, a supporting stud for said slide moved upon each operation of said operating mechanism, and a member operated by said operating mechanism for neutralizing the effect upon said slide of the movement of said supporting stud.
20. In a machine of the class described, a plurality of totalizers, actuators therefor, an operating mechanism, means operated by said operating mechanism normally conditioned for causing the engagement of all of said totalizers with the actuators and connections from said operating mechanism for normally rendering said means ineffective on one of said totalizers.
21. In a machine of the class described, a plurality of totalizers, actuators therefor, an operating mechanism, a member for each of said totalizers adapted to control the engagement of the related totalizer with the actuators, connections from said operating mechanism normally conditioned for causing the engagement of all of said totalizers with the actuators and means operated by said operating mechanism for neutralizing the action of said connections upon all but one of said totalizers.
22. In a machine of the class described, a plurality of totalizers, actuators therefor, an operating mechanism, a member for each of said totalizers adapted to control the engagement of the related totalizer with the actuators, connections from said operating mechanism normally conditioned for causing all of said members to engage their respective totalizers with the actuators, means operated by certain of said connections for neutralizing the action of said connections upon all but one of said members.
23. In a machine of the class described, a plurality of totalizers, actuators therefor, an operating mechanism, a member for each of said totalizers adapted to control the engagement of the related totalizer with the actuators, connections from said operating mechanism normally conditioned for causing all of said members to engage their respective totalizers with the actuators, means operated by certain of said connections for neutralizing the action of said connections upon all but one of said members, and a lever for disabling said means.
24. In a machine of the class described, a plurality of totalizers, actuators therefor, an operating mechanism, a slide for each of said totalizers for controlling the engagement of the related totalizer with the actuators, a movable stud connected with all of said slides and movable upon each operation of the machine, and connections from the operating mechanism for neutralizing the effect of the movement of said stud upon all but one of said slides.

In witness whereof I have signed my name hereto this 5th day of December, 1924.

CHARLES W. GREEN.
